UNITED STATES PATENT OFFICE.

JOHN CHILCOTT, OF BROOKLYN, NEW YORK.

IMPROVEMENT IN HOT-AIR FURNACES.

Specification forming part of Letters Patent No. 51,921, dated January 9, 1866; antedated December 28, 1865.

To all whom it may concern:

Be it known that I, JOHN CHILCOTT, of the city of Brooklyn, in the county of Kings and State of New York, have invented a new and useful Improvement in Air-Heating Furnaces; and I do hereby declare that the following is a full, clear, and exact description of the same, reference being had to the accompanying drawings, forming part of this specification, in which—

Figure 1 is a transverse vertical section of a series of flues and intervening air-heating passages illustrating my improvement, the plane of such section being indicated by a line, *z z*, in Figs. 2 and 4. Fig. 2 is a longitudinal vertical section of the same, in the plane indicated by the line *x x* in Fig. 1. Fig. 3 is a longitudinal vertical section of the same, in the plane indicated by the line *y y* in Fig. 1. Fig. 4 is a plan view of the interiors of the flues, as exhibited by the removal of the upper slab, of which the series of flues and air-heating passages are composed.

Similar letters of reference indicate corresponding parts in the several figures.

This invention consists in a novel arrangement and construction of the flues and air-passages of an air-heating furnace, whereby the heat is very effectively and economically employed and provision is afforded for cleaning out the flues whenever necessary.

To enable others skilled in the art to make and use my invention, I will proceed to describe its construction and operation.

The flues *A A*, represented of circular form in their transverse section, are arranged parallel with each other in two or more tiers, one above another, those in each tier having communication at opposite ends, alternately, in such manner, as represented in Fig. 4, that the gaseous products of combustion, entering the first tier from the fire-place through an opening, *b*, Figs. 1 and 2, circulate back and forth, as indicated by arrows in that figure, through one flue after another before passing out through an upward outlet, *a*, Figs. 1 and 4, to the first flue of the next tier above, through which they circulate back and forth in a similar manner before escaping through a similar outlet to the next tier, the circulation being continued in this way through the several tiers before es-

caping from the uppermost one through an opening, *c*, to the chimney or uptake. The flues in the several tiers are so arranged relatively to each other, as shown in Fig. 1, as to leave room between them for the air-heating passages *B B*, which are represented of quadrangular form in their transverse section, and are arranged parallel with and between the flues in tiers, one above another, in such manner that each of said passages is nearly surrounded by four flues, two above and two below, and thereby heated on all sides.

The air-heating passages are separate and independent of each other, and open at both ends in such manner that a free circulation of air may take place through them. In order to provide for a free circulation of air through the said passages, the said passages and flues should have a slight inclination from the horizontal position, so that the air entering at their lower ends in a cool state, and becoming heated, may circulate upward. The flues and air-passages, so arranged, may be arranged directly over the fire-place, or in any convenient position which will allow the gaseous products of combustion to enter the opening *b*, and a suitable air-trunk or conductor should be properly arranged in relation to the air-passages to convey the heated air to where it is required, either for warming a building, heating a kiln or drying-room, or for any other purposes.

The flues and air-heating passages are constructed in a series of slabs of fire-brick or plates of cast-iron, *C D D E*, which are placed one upon another, and fitted together with tongues and grooves *ee*, to keep them in their proper relative positions and prevent such leakage of air and gas as would be prejudicial to the operation of the apparatus. The several flues and air-passages are constructed half in one and half in the next slab or plate above or below. The lowest slab or plate, *C*, has formed in its upper side only half of each of its lowest tier of flues, and the top slab or plate, *E*, has formed in its lower side only the upper half of each of the highest tier of flues. The intervening slabs or plates *D D* have each formed in one side half of each of the flues of one tier, and in the other side half of each of the air-passages. The slabs or plates thus constructed can be easily put together in building and

taken apart for cleaning the flues by any person having no pretension to mechanical skill.

What I claim as my invention, and desire to secure by Letters Patent, is—

1. The arrangement, substantially as herein described, of two or more tiers of flues, A A, forming one continuous series, through which the gaseous products of combustion from any suitable fire-place circulate one after the other, and a series of intervening separate and independent air-passages heated by the said flues.

2. The construction of such continuous series of flues and intervening air-passages in slabs or plates C D D E, in which each of the said flues and air-passages are half in one and half in the next slab, a plate above or below it, substantially as herein described.

JOHN CHILCOTT.
